[57] CLAIM

The ornamental design for a catheter connector for drainage tubes, as shown and described.

DESCRIPTION

FIG. 1 is a perspective view of a catheter connector for drainage tubes showing my new design;

FIG. 2 is a top plan view thereof;

FIG. 3 is a bottom plan view thereof;

FIG. 4 is a left side elevational view thereof, the right side view being identical; and

FIG. 5 is a front elevational view thereof, the rear view being identical.

The broken line showing of the tubes in FIG. 1 is for illustrative purposes only and forms no part of the claimed design.

Fig. 1.
